UNITED STATES PATENT OFFICE

WILLIAM P. MOSELY, OF STAMFORD, CONNECTICUT, ASSIGNOR TO THE YALE & TOWNE MANUFACTURING COMPANY, OF STAMFORD, CONNECTICUT

SAFE DEPOSIT LOCK

Application filed July 28, 1928. Serial No. 296,048.

My invention relates to improvements in safety deposit locks and is a modification of my invention described in Patent 1,432,720 for a safety deposit lock issued October 17, 5 1922.

In that patent there is shown the combination of a safety deposit lock having the usual guard and change tumblers and a key designating character which is held from view by 10 a screw. The screw is adapted to maintain the change tumblers in inoperative position while maintaining the designating character concealed, and it is necessary to remove the screw to release the tumblers in order to view 15 the key designating character.

For a better understanding of the invention, I shall now refer to the drawing wherein are shown two modifications of my invention. Fig. 1 is a top view of a washer comprising part of my invention, while Fig. 2 is 20 an elevation of a screw comprising the invention and shown in cooperation with the washer. Figs. 3 and 4 are end and elevation views of the screw, comprising a modification 25 of the invention illustrated in Figs. 1 and 2. Fig. 5 is a view of the back plate of a safe deposit box showing the invention applied thereto. Fig. 6 is a front view of the lock with the cover removed, showing the tumbler 30 arrangement.

While I will describe below the invention as shown in this application, a perusal of my patent, indicated above, will be helpful insofar as it indicates in more detail the significance of the invention described herein.

As shown in Figs. 1 and 2, I have found it expedient to employ a washer 10 which is adapted to carry the key designated character 4150. This washer is held under the head of 40 the screw 11 which maintains the washer against the casing 15 as is clearly shown in Fig. 5. When the screw is in its operative position secured to the bolt 14 by means of the screw-threaded portion 14a, its extension 45 13a is adapted to hold the tumblers inactive as illustrated in Fig. 6, and the designating character 4150 will be held in a concealed position as is clear from Fig. 5. It is then necessary to remove the screw and release the 50 various tumblers so that the washer may be

withdrawn and exposed to view in order that the key designation be read.

Figs. 3 and 4 show a modification of Figs. 1 and 2, in which the key designating character is carried on the rear face 12 of the 55 screw 11. It is quite obvious that the character 4150 will thus be held concealed as long as the screw is maintained in its active position for maintaining the tumblers 13 inoperative. Thus, the underlying principle 60 of the invention is the maintenance of the designating character out of view by utilizing directly the means which hold the lock inoperative.

While I have shown two modifications of 65 my invention, it is quite evident that other variations of the same within the scope of the appended claims will occur readily to those skilled in the art.

I claim:

1. In a lock, a plurality of tumblers, a key guide in said lock whereby said tumblers may be operated, means leading into said lock independently of said keyway, and adapted to hold said tumblers in inoperative position, 75 and a key designating character carried by said tumbler holding means.

2. In a lock, operating mechanism, a screw adapted to enter said lock and hold said operating mechanism in inoperative position, 80 and a key designating character carried by said screw.

3. In a lock, a plurality of tumblers, a key guide leading into said lock whereby said tumblers may be operated, means adapted to enter said lock other than through said keyway and acting to maintain said tumblers inoperative, and a key designating character carried by said means.

4. In a lock, a bolt having a fence, a tumbler having a gating, a key guide in said lock whereby said tumbler may be operated, means adapted to enter said lock other than through said keyway, and acting to maintain said tumbler gating in line with said bolt fence, 90 and a key designating character carried by said means.

5. In a lock, a bolt having a fence, a tumbler having a gating for said fence, a screw adapted to enter said lock and acting to 100

maintain said tumbler gating alined with the bolt fence, and a key designating character carried by said screw.

6. In a lock, a bolt, a plurality of tumblers for controlling said bolt, a casing for said lock, a screw adapted to enter said lock casing, said screw having means acting to maintain said tumblers in inoperative position, and a key designating character carried under the head of said screw.
7. In a lock, a bolt, a plurality of tumblers for controlling the operation of said bolt, a casing for said lock, a screw having a body portion adapted to enter said casing, said body portion having an extension adapted to maintain said tumblers in inoperative position, and a key designating character carried under the head of said screw outside the lock casing.
8. In a lock, a lock casing, a bolt, a plurality of tumblers having gatings for controlling the action of said bolt, a screw having body and head portions, said body portion being adapted to enter the lock casing while said head remains outside, said body portion being operable while within the casing to maintain the lock mechanism inoperative, and a key designating character carried under the head of said screw and maintained hidden while said body portion is within said casing.
9. In a lock, a lock casing, a bolt having a fence, a plurality of tumblers having gatings for said fence, a slot in said casing, a screw adapted to enter the casing through said slot and to be screwed into the bolt, said screw acting to maintain the tumbler gatings alined with the fence, and a key designating character carried by said screw.
10. In a lock, a lock casing, a bolt having a fence, a plurality of tumblers for said bolt, said tumbler having gatings for said bolt fence, a longitudinal slot in said casing, a screw adapted to enter a portion of the bolt and have its head rest in said slot, an extension on said screw adapted to maintain the tumbler gatings alined with the bolt fence, and a key designating character carried under the head of said screw.
- Signed at Stamford, in the county of Fairfield and State of Connecticut, this 27th day of July, A. D. 1928.

WILLIAM P. MOSELY.
